GERMICIDAL COMPOSITIONS

Harold G. Kolloff, Kalamazoo, Mich., assignor to
The Upjohn Company, Kalamazoo, Mich., a
corporation of Michigan

No Drawing. Application October 28, 1944,
Serial No. 560,906

6 Claims. (Cl. 167—19)

1

This invention relates to germicidal compositions and is particularly directed to a mixture of a long-chain alkylamine salt and a mercurial.

Certain of the alkylamines and particularly those containing long-chain structures of eight or more carbon atoms are known to exert a germicidal effect upon certain micro-organisms. However, the concentrations of these compounds required for use as general germicidal and disinfectant materials is high if control is to be obtained against such representative and resistant bacteria as *Staphylococcus* organisms. Their use has been limited in spite of the fact that they had been widely publicized as comparatively non-poisonous substitutes for the more conventional mercurial type germicide and disinfectant.

Similarly the mercurials are recognized as having limitations in germicidal use. Not infrequently, at the concentrations required for effective control of micro-organisms, these materials are very toxic to humans and may also be corrosive to the skin. Much interest has been developed in the search for substitutes therefor.

It is an object of the present invention to provide compositions adapted for germicidal, disinfectant, and bactericidal use which will be more effective against micro-organisms generally than the amine and mercury products heretofore employed. It is a further object to supply such a composition which will be effective against *Staphylococcus* organisms and more particularly *Staphylococcus aureus*. Other objects will become apparent from the following specification and claims.

According to the present invention, it has been discovered that compositions including a long-chain alkylamine salt and a water-soluble mercuric salt are much more effective against bacteria and particularly *Staphylococcus* organisms than either the amine salt or the mercuric salt alone. In such combinations these two classes of germicidal materials appear to exert a co-operative or synergistic effect, whereby a composition containing both is effective to a degree greatly in excess of what might be anticipated from a knowledge of the germicidal activities of the individual components of such composition. At the high dilutions of such mixture found effective the hazards normally attendant in the utilization of the water-soluble mercuric salt are greatly reduced. Furthermore, the combination appears to be more effective against a wider variety of organisms than can be controlled with either constituent alone.

The long-chain alkylamine salts employed in

2

accordance with the present invention are those containing at least one alkyl radical of eight or more carbon atoms attached to the amino nitrogen. The preferred compounds are those in which the alkyl radical is straight chain in configuration and particularly of the group consisting of normal-dodecyl, normal-tetradecyl and normal-hexadecyl radicals.

Any suitable mercury salt, preferably water-soluble, may be employed in combination with the acid salt of the long-chain alkylamine provided only that such mercury derivative does not form a precipitate with the amine when the composition is dissolved in water, alcohol, water-alcohol mixtures, or other liquid carrier.

The amounts of alkylamine salt and mercurial adapted to be combined to form compositions having the desired properties vary somewhat with the particular organism to be controlled and the exact nature of the amine salt or mercurial selected. Three parts by weight of the amine salt are generally combined with from one to nine parts of the mercurial. Best results have been obtained when three parts of the amine salt are employed in combination with from two to four and one-half parts of mercurial. The latter range of proportion constitutes a preferred embodiment of the invention.

The new germicidal compositions may be employed in any suitable form. In a preferred embodiment, the combination of toxicants is dissolved, or otherwise dispersed, in an alcohol or other organic solvent, water, or mixture of water and solvent to produce a germicidal tincture or solution. If this liquid composition is to be used as a concentrate, a relatively high proportion of the toxicant mixture may be incorporated therein. If the liquid is to be employed for germicidal purposes without further modification only a small fraction of one percentum of the toxicant combination need be dissolved therein. Generally, from 0.01 per cent to 10 per cent of dissolved toxicant yields a satisfactory concentrate and one part per forty thousand or less is effective germicidally in the ultimate dilution, as illustrated by tests according to the F. D. A. method hereinafter mentioned.

Further embodiments of the invention include the incorporation of the toxicant mixture in finely divided carriers to produce powders adapted to be dusted on infected surfaces for the control of bacteria or to be dispersed in water to produce germicidal dispersions. Such powders conveniently may be prepared by dissolving the desired amount of toxicant mixture in a volatile

organic solvent, wetting the carrier therewith, and thereafter evaporating off the solvent. Any desired amount of toxicant may be incorporated into the powder in this fashion. Suitable carriers include talc, diatomaceous earth, bentonite, and the like. Similarly the toxicant composition may be incorporated into ointments or lotions using the conventional carriers and bases and regulating the concentration of the toxicant to meet the requirements for which the ultimate product is designed.

Various coloring materials, perfumes and the like, may be included in the compositions as described provided only that they do not react with either constituent of the mixture or inhibit the germicidal action thereof.

The following examples illustrate the invention but are not to be construed as limiting. In these examples, the amine salts were employed as tinctures prepared by dissolving one gram of the salt in a mixture of 500 milliliters of ethyl alcohol, 100 milliliters of acetone, and 400 milliliters of water, which mixture is hereinafter referred to as the "standard solvent." All results are given in terms of one part by weight of the solid amine salt in a stated number of parts by weight of solvent. Similarly, tinctures were prepared of the mercurials and the effectiveness of the latter in terms of dilution refers to the number of parts by weight of solid mercurial in the dilution reported. An exception is found in the case of mercuric chloride where water was employed as the solvent.

EXAMPLE 1

One gram of di-normal-octylamine hydrochloride was dissolved in one liter of the standard solvent as above defined to produce a germicidal concentrate. The effectiveness of this tincture was determined against *Staphylococcus aureus* at 37° centigrade, according to the method developed by the United States Public Health Service, Hygienic Laboratory of the Food and Drug Administration, United States Department of Agriculture (Circular 198, published December 1931). In this operation, the tincture was found effective at a dilution of one part by weight of amine in 9,000 parts by weight of water.

In further determinations, a similar tincture of Mercarbolide (ortho-hydroxy-phenyl-mercuric chloride) and a 0.2 per cent solution of mercuric chloride in water were found to be effective at dilutions of 1-2,000 and 1-500 in water, respectively.

Compositions were prepared in which one gram of Mercarbolide and one gram of amine salt were dissolved in one liter of the standard solvent. The resulting germicidal solution was effective against *Staphylococcus aureus* at a dilution of 1-40,000 in water, based on the active ingredients in the dilution. A similar effectiveness was found for a mixture of equal volumes of amine salt tincture and the aqueous solution of mercuric chloride.

EXAMPLE 2

A tincture containing 0.1 per cent by weight of normal-tetradecylamine sulfate was prepared and tested against *Staphylococcus aureus*, substantially as described in Example 1 and found to be effective at a dilution of 1-12,000 in water. When one gram of normal-tetradecylamine and one gram of Mercarbolide were dissolved in one liter of standard solvent, the resulting product was effective against *Staphylococcus aureus* in 75

an aqueous dilution of 1-40,000. When one gram of normal-tetradecylamine and one gram of mercuric chloride were dissolved in one liter of standard solvent, the resulting product was effective against *Staphylococcus aureus* in an aqueous dilution of 1-30,000.

EXAMPLE 3

A similar operation was carried out in which a 0.1 per cent by volume tincture of N,N-dimethyl-normal-dodecylamine hydrochloride was employed. This solution was effective against *Staphylococcus aureus* at a dilution of 1-6,000 with water. Compositions obtained by mixing in one liter of standard solvent one gram of the amine salt with either one gram of Mercarbolide or one gram of mercuric chloride were found effective against *Staphylococcus aureus* in aqueous dilutions of 1-40,000 and 1-30,000, respectively.

EXAMPLE 4

Other long-chain alkylamine salts were substituted for those shown in Examples 1, 2 and 3 and combined with the water-soluble mercurial salts to obtain compositions of comparable effectiveness. The following table illustrates the results obtained. The columns are identified as follows:

30	I. The amine salt used.
25	II. Maximum effective dilution of a tincture of one gram of the amine salt in one liter of standard solvent in terms of one part by weight of the solid amine salt to the stated number of parts by weight of solvent.
30	III. Maximum effective dilution of a tincture of one gram of the amine salt and one gram of Mercarbolide in one liter of the standard solvent in the same terms as stated for column II.
35	IV. Maximum effective dilution of a tincture of one gram of amine salts and one gram of mercuric chloride in one liter of the standard solvent in the same terms as stated for column II.
40	II.

For purposes of comparison the effective dilution of a tincture of Mercarbolide comprising one gram thereof in one liter of standard solvent and the effective dilution of a 0.2 per cent solution of mercuric chloride are also shown and for convenience placed under columns I and II.

	I	II	III	IV
55	Mercarbolide.....	1-2,000	-----	-----
	Mercuric Chloride.....	1-500	-----	-----
	normal-Dodecylamine hydrochloride.....	1-15,000	1-35,000	1-40,000
	normal-Tetradecylamine hydrochloride.....	1-15,000	1-40,000	1-25,000
	normal-Hexadecylamine hydrochloride.....	1-3,000	1-25,000	-----
	normal-Octadecylamine hydrochloride.....	1-3,000	1-25,000	-----

65	Di-normal-octylamine sulfate.....	1-12,000	1-40,000	-----
	Di-normal-octylamine acetate.....	1-12,000	1-35,000	-----

EXAMPLE 5

Other compositions which may be similarly employed for the control of *Staphylococcus aureus* or other representative organisms, such as

Eberthella typhi, *Epidermophyton interdigital*, et cetera, include the following:

Composition A

0.1% by weight tincture of normal-hexadecylamine hydrochloride	parts by volume	3
0.1% by weight tincture of Mercarbolid	parts by volume	1
Pine oil	per cent by weight	0.5

Composition B

Di-normal-octylamine acetate	per cent by weight	0.1
Mercuric chloride	grams	0.03
Talc	do	1,000

Composition C

	Grams
N,N-Dimethyl - normal-tetradecylamine hydrochloride	0.001
Merthiolate (sodium-ethylmercuri-thiosalicylate)	0.0015
Lanolin	100

Composition D

	Milligrams
0.1% by weight tincture of N,N-dibutyl-normal-tetradecylamine hydrochloride	600
0.1% by weight tincture of Metaphen (anhydride of 4-nitro-5-hydroxymercuri-o-cresol)	400

Composition E

	Milligrams
0.1% by weight tincture of N-benzyl-normal-dodecylamine hydrobromide	300
0.1% by weight solution of mercury oxy-cyanide	100

The amine salt compounds, as employed in the foregoing examples, may be generically described as the soluble acid salts of alkylamines having the general formula:

wherein R represents an alkyl radical containing at least 8 carbon atoms and each R' represents alkyl, aralkyl, such as benzyl, aryl, cycloalkyl, or hydrogen. Representative members of this class of compounds adapted to be employed substantially as shown in the foregoing compositions include secondary-octylamine hydrochloride, 2-ethyl-normal-decylamine hydrobromide, tri-normal-octylamine sulfate, N - methyl - normal-tetradecylamine propionate, N,N-dimethyl-normal-octylamine metho-sulfate, and the like.

Other solvents which may be employed as carriers for the compositions of amine salt and mercurial as herein disclosed include methanol, propanol, isopropanol, ethylene glycol, diethylene glycol, carbitol, Cellosolve, methyl Cellosolve, methyl carbitol, acetone, or any mixture of two

or more of these solvents or mixtures thereof with water.

I claim:

1. A germicidal composition having synergistic germicidal effect against *Staphylococcus aureus* including as active germicidal ingredients (1) an acid addition salt of an alkyl amine containing at least one alkyl radical having from 8 to 18 carbon atoms, inclusive, and (2) a mercurial selected from the group consisting of mercuric chloride and ortho-hydroxy-phenyl-mercuric chloride.

2. A germicidal composition having synergistic germicidal effect against *Staphylococcus aureus* including as active germicidal ingredients (1) an acid addition salt of an alkyl amine containing at least one alkyl radical having from 8 to 18 carbon atoms, inclusive, and (2) mercuric chloride.

3. A composition according to claim 2 containing approximately three parts by weight of the amine acid addition salt and from one to nine parts of mercuric chloride.

4. A germicidal composition having synergistic germicidal effect against *Staphylococcus aureus* including as active germicidal ingredients (1) an acid addition salt of an alkyl amine containing at least one alkyl radical having from 8 to 18 carbon atoms, inclusive, and (2) ortho-hydroxy-phenyl-mercuric chloride.

5. A composition according to claim 4 containing approximately three parts by weight of the amine acid addition salt and from one to nine parts of ortho-hydroxy-phenyl-mercuric chloride.

6. A germicidal composition having synergistic germicidal effect against *Staphylococcus aureus* which comprises approximately 0.1 percent by weight of normal-tetradecylamine sulfate and 0.1 percent by weight of ortho-hydroxyphenyl-mercuric chloride dissolved in a mixture of approximately 50 volumes of ethyl alcohol, 10 volumes of acetone and 40 volumes of water.
